UNITED STATES PATENT OFFICE.

CLARENCE H. BALL, OF WEBSTER CITY, IOWA.

DESIGN FOR A HARNESS SNAP-HOOK.

SPECIFICATION forming part of Design No. 32,359, dated March 20, 1900.

Application filed February 6, 1900. Serial No. 4,286. Term of patent 7 years.

To all whom it may concern:

Be it known that I, CLARENCE H. BALL, a citizen of the United States, residing at Webster City, in the county of Hamilton and State of Iowa, have invented and produced a new and original Design for a Snap-Hook, of which the following is a specification, reference being had to the accompanying drawings, forming part thereof, in which—

Figure 1 is a perspective view showing my new design complete as required for practical use. Fig. 2 is a longitudinal sectional view showing an upward swell in the solid, straight, and rigid portion contacting the free end portion that is doubled backward over the straight rigid portion.

The letter A designates the large end portion of the hook that gradually diminishes in width from end to end, and B is the narrow

end portion. The solid large end portion is 20 corrugated to produce an upward artistic swell C, that contacts with the under side of the narrow end portion B. The broad end has rounded corners and a transverse slot D, and the narrow end terminates in an ornamental head F.

Having described my invention, what I claim as new, and desire to secure by Letters Patent, is—

The design for a snap-hook, as herein shown 30 and described.

In testimony whereof I have signed my name to this specification in the presence of two subscribing witnesses.

CLARENCE H. BALL.
